DESIGN FOR A PANEL MAT

William J. Adams, Jr., Hartsdale, N. Y., assignor
to Bell Telephone Laboratories, Incorporated,
New York, N. Y., a corporation of New York

Application December 28, 1934, Serial No. 54,625

Term of patent 14 years

To all whom it may concern:

Be it known that I, William J. Adams, Jr., a citizen of the United States of America, residing at Hartsdale, in the county of Westchester and State of New York, have invented a new, original, and ornamental Design for a Panel Mat, of which the following is a specification, reference being had to the accompanying drawings, forming a part thereof.

Fig. 1 of the drawings is a front face plan view of the panel mat showing my new design.

Fig. 2 is a front face plan view of a portion of the panel mat considerably enlarged relative to

Fig. 1 and taken in the central portion of the panel mat; and

Fig. 3 is a view in cross-section of the panel mat taken on the line 3—3 in Fig. 2 and viewed in the direction indicated by the arrows. Fig. 3 is drawn to the same scale as Fig. 2.

I claim:

The ornamental design for a panel mat as shown.

In witness whereof, I hereunto subscribe my name this 26th day of December, 1934.

WILLIAM J. ADAMS, JR.
